R. W. KUMLER

HINGED CONNECTION

Filed April 11, 1923

UNITED STATES PATENT OFFICE.

ROY W. KUMLER, OF DETROIT, MICHIGAN.

HINGED CONNECTION.

Application filed April 11, 1923. Serial No. 631,278.

To all whom it may concern:

Be it known that I, Roy W. KUMLER, a citizen of the United States, residing at Detroit, county of Wayne, State of Michigan, 5 have invented a certain new and useful Improvement in Hinged Connections, and declare the following to be a full, clear, and exact description of the same, such as will enable others skilled in the art to which it 10 pertains to make and use the same, reference being had to the accompanying drawings, which form a part of this specification.

My invention relates to improvements in hinged connections.

15 In certain classes of hinged connections in which relatively swinging sections are employed, the swinging of one pivotally supported panel section relative another causes an exposed surface of such panel to rub 20 against the other panel at the hinge joint and mutilate the contacting surfaces.

In the specific embodiment of my invention herein illustrated I have preferred to show my improvement in association with 25 the hinged panels of an automobile hood. The particular hinged construction in association with which I have illustrated my invention is that described in United States Patent #1,247,715 dated November 27, 1917. 30 In this patent an automobile hood is used to illustrate the invention therein described and the hinge construction is such that the surfaces of the swinging sections adjacent the hinge joint rub against each other as one 35 section is swung relative the other. This rubbing of the one section against the other breaks the enamel and mars the exposed surface of the panel at the hinge. My improvement eliminates this undesirable result.

40 An object is to provide in a hinged connection means to eliminate the rubbing contact of the swingable section at the hinge which produces defacement of the exposed surface of such swingable section.

45 A further object is to provide means to maintain yielding pressure on a pivotally supported swinging section of a hinged construction to hold such section away from the section to which it is hinged, thereby preventing abrasive contact of the sections and

eliminating surface defacement at the hinge joint.

Further important objects of the invention relate to a hinged connection in which, by means of a suitable arrangement of 55 springs, yielding pressure is maintained on the relatively swingable sections to hold them apart during the swinging movement; and in a preferred form of a specific embodiment to a hinged connection in which 60 springs are arranged between the pivotally supported sections to exert pressure thereon in opposite directions; and to an arrangement of stops between in-turned adjacent edges of swingable panel sections of a hinged 65 connection to maintain distance therebetween.

In the drawings,—

Figure 1 is a broken away sectional view through an automobile hood equipped with 70 my improvement.

Fig. 2 is an enlarged fragmentary section of a view of the hinge structure.

Fig. 3 is a sectional view similar to Fig. 2 showing a different form of spring.

Fig. 4 and Fig. 5 are sectional views similar to Fig. 2 showing separate forms of spring structures.

Fig. 6 is a perspective of a preferred form of spring.

Fig. 7 is a perspective of the end piece used in the tubular member.

Fig. 8 is a perspective of a modified form of end piece.

Fig. 9 is a perspective showing the swing- 85 ing panel sections and hinge connection.

Fig. 10 is a fragmentary plan showing the swinging panels and a portion of the support therefor.

In the specific hinge construction here employed to illustrate my improvement, an object is to provide yielding means to maintain pressure on a pivotally supported hood panel section to prevent such panel from contacting with the panel to which it is hinged so as to eliminate breaking of the surface enamel and mutilation of the panel adjacent the hinge. In automobile hood construction this rubbing contact of the panel surfaces at the hinge breaks the enamel 95 100.

and exposes the metal to rust and produces an unsightly appearance of the hood panels at the hinge.

In the particular hinge construction in connection with which I have here shown my invention the panel sections have in-turned marginal portions which are received in a longitudinal slot formed in the flattened face of the tubular casing. Each in-turned marginal portion is bent back upon itself within the casing as shown. In this construction one panel section may swing relative the other to lie flat thereagainst, as shown in Fig. 2 in dotted outline. The casing itself is swingable relative the panel sections and when one of the panel sections is swung from the position shown in Fig. 1 to that shown in Fig. 2, or through an arc of approximately 180 degrees, the casing itself swings relative the panel through an arc of approximately 90 degrees.

I provide means to eliminate the rubbing contact of the adjacent surfaces of the panel sections during this swinging movement. In Figs. 1 and 2 I have shown springs fashioned after the form of the spring shown in perspective in Fig. 6. The opposite in-turned flange portions of the panel sections are provided with apertures to receive the ends of the springs disposed between the panels.

In the drawing, one panel section is indicated as 10, a second panel section as 11, and a tubular casing, here shown in the form of a half-round, though obviously it might take another shape, as 12. The flattened face of this casing is longitudinally slotted at 13. The edge of each panel section is turned over at 14 into the slot in the casing. This in-turned marginal portion of the panel section is doubled back as at 15 and opposite marginal portions of adjacent panels are provided with opposite apertures 16 to receive the opposite ends of a spring 17 which is held under compression between the panels, as shown in Figs. 1 and 2, so as to exert yielding pressure outwardly on the panels in opposite directions to hold the panels apart and to prevent rubbing contact of the panels at the hinge joint during the swinging thereof. These springs may be used in such number as is found necessary.

In Fig. 3 a slightly different type of compression spring is employed, this spring being corrugated, but the result accomplished thereby is the same.

In Figs. 4 and 5 expansion springs are used. These springs loop through the apertures in the in-turned flanges of the panels on the outside and exert yielding pressure to hold the panels apart.

The casing is provided with end pieces 18 which may be secured in the casing by screws 19 received in the apertures 19a. The bottom of the end pieces is cut away as

at 20 to provide a drainage outlet for the casing. The upper surface of the end pieces is cut away at 21 to receive the in-turned flange 14 of the panel section when the same is rotated by the swinging of the panel.

In Fig. 8 I have shown an end piece provided with a teat-like projection 22 and an end extension 23 positioned on a line with the apex of the projection. This projection extends upwardly from the bottom of the cut out portion in the face of the end piece between the opposite in-turned edges of the panel sections. The lateral faces of this projection are concaved so that when one panel is swung relative the other the in-turned marginal portion rides over this concaved face to prevent rubbing contact of the panel sections. The end extension 23 also serves to hold separate panel sections apart.

What I claim is:

1. In a hinged connection, in combination, two panels hinged together to permit swinging movement of one panel relative the other, said panels having in-turned edges adjacent the hinge joint, and yieldable means engaging said panels at the joint to exert pressure thereon to hold them apart. 90

2. In a hinged connection, in combination, two panels having in-turned adjacent edges and being hinged together to permit swinging movement of one panel relative the other, and means interposed between in-turned edges of said panels to prevent abrasive contact of said edges during swinging movement. 95

3. In a hinged connection, in combination, two panels having in-turned adjacent edges and being hinged together to permit swinging movement of one panel relative the other, and resilient means engaging the in-turned edges of said panels tending to hold them yieldingly apart. 100

4. In a hinged connection, in combination, two panels hinged together to permit swinging movement of one panel relative the other, said panels having in-turned edges provided with opposed apertures, spring means engaged in said apertures to exert pressure on said panels in opposite directions. 110

5. In a hinged connection, two panels having in-turned adjacent edges received within a slotted casing to permit swinging movement of one panel relative the other, and yieldable means engaging the in-turned edges of said panels to exert pressure thereon in opposite directions. 115

6. In a hinged connection, in combination, two panel sections having in-turned adjacent edges, a longitudinally slotted casing, the in-turned edges of said panel sections received within the slotted opening in said casing to permit swinging movement of one panel section relative the other, and means interposed between the in-turned 125

edges of said panel sections to hold the same apart during the swinging movement of said panel sections.

7. In a hinged connection, in combination, two panel sections having in-turned adjacent edges, a longitudinally slotted casing, the in-turned edges of said panel sections received within the slotted opening in said casing to permit swinging movement of

one panel section relative the other, and 10 spring means within said casing engaging the in-turned edges of said panel sections to exert pressure thereon in opposite directions.

In testimony whereof, I sign this specific- 15

ROY W. KUMLER.
